UNITED STATES PATENT OFFICE.

EZRA H. STAFFORD, OF MUSKEGON, MICHIGAN.

DESIGN FOR A SCHOOL DESK AND SEAT.

SPECIFICATION forming part of Design No. 24,975, dated December 10, 1895.

Application filed November 9, 1895. Serial No. 568,497. Term of patent 3½ years.

To all whom it may concern:

Be it known that I, EZRA H. STAFFORD, a citizen of the United States, residing at Muskegon, in the county of Muskegon and State 5 of Michigan, have invented a certain new and original Design for a School Desk and Seat; and I do declare the following to be a full, clear, and exact description of the invention, such as will enable others skilled in the art to o which it appertains to make and use the same.

My invention relates to a new design for a combined school desk and seat.

In the drawing, in which I represent my design in perspective, 1 denotes the standards 5 of the desk, 2 the desk-top, 3 the seat, and 4 the seat-back.

The leading features of the design are the standards, which consist of the front posts 5, the upper end of which is curved rearward

and downward, and thence upward, as shown 20 at 6; the rearward posts 7, which are curved forward and thence rearward, as shown at 8; the arched bar 9; the desk-support 10; the open scrollwork 11 arranged between the top 25 of the desk and the cross-bar 12; and the pin scrollwork 13, which is arranged between the back of the seat and the rear post and between the curved portions of the front post and the lower arched cross-bar.

What I claim is—

The design for a combined school desk and seat, as herein shown and described. 30

In testimony whereof I affix my signature in presence of two witnesses.

EZRA H. STAFFORD.
